[54] ARYLOXY SUBSTITUTED PHOTOGRAPHIC COUPLERS AND PHOTOGRAPHIC ELEMENTS AND PROCESSES EMPLOYING SAME

[76] Inventor: Philip T. S. Lau, Kodak Park Works, Rochester, N.Y. 14650

[21] Appl. No.: 463,425

[22] Filed: Feb. 3, 1983

[52] U.S. Cl. 564/218; 260/509; 548/373; 548/374; 564/123; 564/173; 564/443

[57] ABSTRACT

Couplers of good reactivity contain an aryloxy coupling-off group having in an ortho position a polarizable carbonyl, sulfonyl or phosphinyl substituent group which is free of photographic dye groups and photographic reagent groups.
